No. 36,526.

Patented August 25, 1903.

UNITED STATES PATENT OFFICE.

EDWIN NAHR, OF NEW ORLEANS, LOUISIANA.

DESIGN FOR A SMOKE-RING MAKER.

SPECIFICATION forming part of Design No. 36,526, dated August 25, 1903.

Application filed June 17, 1903. Serial No. 161,932. Term of patent 7 years.

To all whom it may concern:

Be it known that I, EDWIN NAHR, a citizen of the United States, and a resident of New Orleans, in the parish of Orleans and State of Louisiana, have invented a new, original, and ornamental Design for a Smoke-Ring Maker.

Reference is to be had to the accompanying drawing, forming a part of this specification, in which the figure is a face view of a smoke-ring maker, showing my design.

I claim as new and desire to secure by Letters Patent—

The ornamental design for a smoke-ring maker as herein shown.

In testimony whereof I have signed my name to this specification in the presence of two subscribing witnesses.

EDWIN NAHR.
